UNITED STATES PATENT OFFICE.

BERTRAM C. CANDEE AND WILLIAM N. PIERCE, OF BUFFALO, NEW YORK, ASSIGNEES
TO PIERCE FUSE CORPORATION, OF BUFFALO, NEW YORK, A CORPORATION OF
NEW YORK.

FUSE.

Application filed June 28, 1920. Serial No. 392,144.

To all whom it may concern:

Be it known that we, BERTRAM C. CANDEE and WILLIAM N. PIERCE, citizens of the United States, residing at Buffalo, in the county of Erie and State of New York, have invented new and useful Improvements in Fuses, of which the following is a specification.

This invention relates to a fuse and has for its object the provision of simple and efficient means for ventilating the casing which encloses the fuse link, so that when the latter blows the gases can escape from the casing without permitting the passage of any flame to the exterior of the fuse.

In the accompanying drawings: Figure 1 is a longitudinal section of our improved fuse taken on a plane at right angles to the plane of the terminals. Figure 2 is a similar view taken on a plane parallel with the plane of the terminals. Figures 3 and 4 are transverse sections taken on the correspondingly numbered lines in Fig. 1. Figure 5 is an end view of the fuse.

Similar characters of reference indicate corresponding parts throughout the several views.

The enclosing casing of the fuse comprises inner and outer tubular body sections 10, 11 30 of insulating material which are movable lengthwise relatively to each other for the purpose of covering and uncovering an opening 12 in the side of the inner section through which the fuse link 14 is introduced into the casing and the remnants of the same are removed when burnt out.

Within opposite ends of the inner body section are arranged metal cup-shaped bushings which have their flanges 15 engaging 40 the bore of the body section and their heads 16 arranged inwardly, so that the concave sides of these bushings face outwardly. A metal cup-shaped baffle is arranged within the outer end of each bushing, the flange 17 45 of this baffle engaging with the bore of the bushing flange and its head 18 being arranged inwardly so that the concave side of the baffle faces outwardly. At one end of the inner body section is arranged a small 50 metal disk 19 which has its edge facing the bore of the outer body section and at the other end of the inner body section is arranged a large metal disk 20 which extends with its margin across the corresponding 55 end of the outer body section.

21 represents a metal cap which fits over one end of the outer body section and is secured thereto by punch pricks 24 and normally bears with its head against the outer side of the small disk. 22 represents a similar metal cap fitting loosely over the other end of the outer body section and secured to the edge of the large disk by punch pricks 23.

25, 26 represent two flat metal terminals 65 of the knife blade type each of which extends lengthwise through the head of one bushing, the head of the companion baffle and the adjacent disk and cap. The inner ends of these terminals are adapted to be 70 connected within the casing by the fuse link which is detachably connected therewith by bolts 27 or other appropriate means, while the outer ends thereof form contacts for engagement with the contacts of a suitable fuse 75 block.

The gases resulting from a blowing fuse escape from the casing through vent openings 28 in the heads of the bushings, vent openings 29 in the heads of the baffles, vent 80 openings 30 in the disks and vent openings 31 in the heads of the caps. Any flame resulting from the blowing of the fuse is however prevented from passing out of the casing to the exterior thereof by means of one 85 or more screens 32 arranged within each bushing next to the outer side of its head, one or more screens 33 arranged within each baffle next to the outer side of its head and a filling 34 of non-combustible wool 90 arranged in each bushing between the screens therein and the inner side of the head of the companion baffle. The screens are preferably constructed of woven wire gauze and the filling preferably consists of steel wool. 95 The screen and filling thus effectually intercept any flames and prevent endangering anything adjacent to the fuse.

35 represents two coupling pins each of which passes transversely through one end 100 of the inner body section, through the companion bushing between the head of the same and the head of the adjacent baffle, and through the adjacent part of the respective terminal, thereby securely uniting these 105 members.

The cap 22 is permanently interlocked with the adjacent terminal 26 by engaging the head of this cap with inwardly-facing shoulders 36 formed on this terminal, as 110

shown in Fig. 2. The cap 21 is however detachably interlocked with the terminal 25 by providing the head of this cap with lips 37 on opposite sides of its center which may be 5 engaged with inwardly-facing shoulders 38 on the terminal 25, as shown in Figs. 2 and 5, upon turning this cap in one direction and disengaged therefrom upon turning this cap in the opposite direction. When the cap 10 21 and terminal 25 are interlocked, the outer casing section is held in its closed position, so as to cover the fuse inlet opening in the inner casing section and when this cap and terminal are unlocked from each other the 15 outer casing section may be slid off the inner casing section to uncover the inlet opening in the latter and permit of renewing the fuse.

As a whole, this fuse is very substantial 20 in construction and not liable to be shattered under the severest use to which the same may be subjected, thereby permitting the same to be used indefinitely with new fuse links. Furthermore, all danger from fire is 25 practically eliminated while retaining the advantage of being easily refillable with new fuses and no likelihood of parts getting out of order.

We claim as our invention:

30 1. A fuse comprising a casing having inner and outer tubular body sections of in-

sulating material, said inner section being provided with a side opening, a comparatively long metal cup-shaped bushing arranged in each end of the inner body section 35 and having its concave side facing outwardly, a metal cup-shaped baffle arranged in the outer end of each bushing and having its concave side facing outwardly, and a metal terminal extending through the heads 40 of each bushing and baffle.

2. A fuse comprising a casing having inner and outer tubular body sections of insulating material, said inner section being provided with a side opening, a comparatively long metal cup-shaped bushing arranged in each end of the inner body section 45 and having its concave side facing outwardly, a metal cup-shaped baffle arranged in the outer end of each bushing and having 50 its concave side facing outwardly, a screen arranged within each bushing next to its head, a screen arranged within each baffle, metal terminals extending through the head of each bushing and the head of the companion baffle, the heads of said bushings and baffles being provided with vent openings, and steel wool arranged in the bushings between the screens therein and the heads of the respective baffles. 55

BERTRAM C. CANDEE
WILLIAM N. PIERCE.
